PACKAGING MACHINE

Peter Jost, Akron, Ohio, assignor, by mesne assignments, of thirty-seven and one-half percent to James Tyrrell as trustee and twenty-five percent to Perry H. Stevens, both of Akron, Ohio

Application December 23, 1937, Serial No. 181,354

8 Claims. (Cl. 226—2)

This invention relates broadly to a packaging machine and more particularly to a device for placing a disk-shaped rubber article in a tubular wrapper.

The device of the present invention is particularly useful in the packaging of collapsible articles. Although the device is described herein in conjunction with the packaging of thin, tubular, rubber articles, closed at one end, with the side walls thereof rolled upon themselves to a point adjacent the closed end wall, it is not intended that it be so limited for the invention can be used for packaging numerous other types of articles. The wrapper for the article is preferably an open ended tubular member relatively smaller in diameter and axial length than the diameter of the article so that when the article and wrapper are assembled a portion of the article extends beyond the ends of the wrapper.

By the present invention there is provided a packaging device which includes, generally: a wrapper feeding assembly for conveying tubular wrappers to a magazine; a receptacle for the articles; reciprocating means which pass thru a wrapper, grip an article and draw it into the wrapper; and discharge means for removing the assembled wrapper and article from the magazine.

In the drawings accompanying and forming a part of this specification, wherein similar reference characters denote corresponding parts:

Figure 1 is a fragmentary, perspective view illustrating apparatus embodying the present invention.

Figure 2 is a fragmentary longitudinal sectional view of the apparatus shown in Figure 1.

Figure 3 is an enlarged fragmentary, sectional detail view illustrating apparatus for discharging the wrapped article from the magazine.

Figure 4 is an enlarged fragmentary, detailed view of a portion of the apparatus, and

Figure 5 is a sectional view taken on the line 5—5 of Figure 4.

In the drawings, there is illustrated apparatus embodying the present invention, including a bed frame 10 which may be supported by any suitable table or framework 11. A vertically disposed cylindrical receptacle 12 is mounted on the top surface of the bed frame 10 adjacent one end thereof, for receiving in stacked relation the articles A to be packaged, as they are discharged from a continuous conveyor 14. The stack of articles disposed within the receptacle 12 is supported on a base 15 having a cut-away portion 16 to provide a space below a portion of the periphery of the bottom article of the stack. An opening 17, in alignment with the surface of the base 16, is provided in the wall of the receptacle 12 through which the bottom article of

the stack may be selectively withdrawn from the receptacle.

Spaced from the receptacle 12 and in longitudinal alignment therewith is a vertically disposed magazine 18, consisting of a pair of rigidly connected spaced members 20 and 21, having opposed slots 22 and 23, respectively, defining a passage 24 for receiving tubular wrappers from a feed tube 19, communicating therewith through an opening 25 in the wall of the member 21. The lower extremities of the slots 22 and 23 terminate in arcuate walls 26 and 27, respectively, which serve to support opposite ends of the lowermost wrapper disposed in the passage 24. Adjacent the lower ends of the slots 22 and 23 the members 20 and 21 have elongated vertically extending openings 28 and 29, respectively, therethrough in alignment with opening 17 in the receptacle 12. Traversing the openings 28 and 29 are horizontal slots 30 and 31 through which the wrapper with an article disposed therein may be removed from the passage 24 of the magazine 18.

The empty tubular wrappers as they are successively introduced into the passage 24 from the feed tube 19 are received by the inner opposed ends of a pair of spring members 32 and 33, pivotally mounted on pins 34, and which serve to position the wrappers in proper position in the passage 24. The wrappers are successively projected past the inwardly projecting portions of the spring members 32 and 33 by a plunger 35 mounted in the passage 24 and normally urged downwardly by a spring 36 supported in a bracket 37 secured to the upper end of the magazine 18. As is shown in Figure 1 the members 20 and 21 of the magazine 18 are supported from the bed frame 10 by means of a bracket arm 38.

The wrapper feeding assembly for conducting empty tubular wrappers to the magazine 18 includes the feed tube 19, one end of which is suitably supported for communication with the opening 25 in the member 20. The other end of the feed tube 19 is mounted for communication with the tubular extension of a funnel-shaped hopper 42 rotatably supported in a bearing block 40 which in turn is supported from the bed frame 10 by means of the bracket 41. The hopper 42 serves to introduce the tubular wrappers in proper position into the tube 19. A sheave 44 mounted on the tubular extension of the hopper 42 receives a drive belt 45 for rotating the hopper. The feed tube 19 is provided with a longitudinal slot 46 through which the periphery of rotating brush 47 extends to assist the movement of the wrappers along the tube 19.

Disposed on the top of the bed frame 10 along each side of a longitudinal slot 48 are ways 49

in which is mounted a reciprocating slide 50. A bolt 51 threaded through the slide 50 and extending through the slot 48 operatively connects the slide to suitable reciprocating means to be described. Secured on the upper surface of the slide 50, by means of bolts 52, is a block 53 having formed on one end thereof a plurality of outwardly extending spaced lugs 54 having secured therebetween a pair of opposed elongated transfer fingers 55 and 56. The ends of transfer fingers 55 and 56 during their reciprocatory movement pass through a tubular wrapper disposed in the magazine 18 and enter the receptacle 12 through the opening 17, grip an article disposed therein and withdraw it from the receptacle and deposit the same within the wrapper in the magazine 18.

Mounted on the bed frame 10 in the path of the reciprocating transfer fingers 55 and 56 are longitudinal spaced opposed rollers 57 and 58 which cooperate to close the space between the transfer fingers when the ends of the fingers are at the extreme end of their outward stroke, thereby causing the fingers to grip the bottom article of the stack disposed in the receptacle 12. The rollers, in operation, are effective to maintain the ends of the fingers in gripping relation with the article during the return stroke of the fingers, and to cause them to release the article before the end of the stroke is reached to permit the removal of the wrapped article from the magazine 18 and the positioning of another wrapper in the magazine prior to the succeeding outward stroke of the transfer fingers. The upper roller 57 is mounted in fixed position in a bracket 59, whereas the lower roller 58 is mounted for vertical movement with respect to the finger 55, serving to move the latter toward the finger 55. The roller 58 is journaled in the end of a block 60 slidably mounted in a sleeve 61 extending through an aperture 62 in the bed frame 10. The lower end of the sliding block 60 is provided with a cam follower or roller 63.

The mechanism for operating the plunger 35 disposed in the magazine 18 for successively projecting tubular wrappers past the spring members 32 and 33 is most clearly illustrated in Figures 1 and 3. This mechanism consists of a member 64, one end of which is pivotally mounted as at 65 in a bracket 66 secured to the bed frame 10. The other end of the member 64 terminates in a pair of spaced arms 67 and 68. The end of the arm 67 has pivoted thereto a link 69, having its upper end secured to an outwardly extending pin 10 carried on the upper end of the plunger 35. The end of the arm 68 is slidably received in a guide slot 71 of a bracket 72. Movement of the member 64 is effected through a cam roller 73 carried by the block 53 and engageable with the lower surface of the member 64. The upper surface of a pivoted plate 74 is adapted to be moved under the lower surface of the arm 68 when the same has been moved to its uppermost position against the compression of the spring 36 by the roller 73 engaging with the member 64, and holds it in said elevated position until the plate 74 is moved out of position by means of a cam, to be described, engageable with the lower end thereof. Upon release of the plate 74 from the arm 68 the plunger 35 is moved downwardly by spring 36 thereby positively moving a tubular wrapper, which has been fed into the passage 24 while the plunger 35 was held in its uppermost position, past the inner ends of the spring members 32 and 33.

Supported beneath the top of the bed frame

10 are a pair of spaced bearings 75 and 76 having journaled therein a cam shaft 77 upon which is keyed a spiral cam element 78. The spiral cam 78 is positioned on the shaft 77 below the slot 48 and has formed therein a groove 79 in which rides a cam follower 80 freely mounted on the end of the bolt 51. Reciprocation of the slide 50 together with the transfer fingers carried thereby is actuated by the cam 78, one revolution thereof effecting a complete reciprocation of the slide 50. The shaft 77 also has cams 81 and 82 secured thereon, cam 81 engaging the lower end of the pivotal plate 74 and serving to pivot the same and thereby move the upper surface thereof into and out of engagement with the lower surface of the arm 68, during predetermined portions of a single rotation of the shaft 77. The cam 82 is so positioned on the shaft 77 as to be engaged by the cam follower 63 carried on the lower end of the slideable block 60. The cam 82 is so formed and positioned on the shaft 77 that the roller 58 actuated thereby urges the transfer finger 56 toward the finger 55 on the return stroke of the fingers, releasing the finger 56 just prior to the end of the return stroke thereby releasing the article between the ends of the fingers 55 and 56. The release of the article by the fingers is so timed that the article is deposited within a tubular wrapper positioned within the magazine 18.

Mounted on the shaft 77 between the cam 82 and the bearing 75 is a disk 83, the periphery of which extends through a transverse opening 84a in the bed frame 10 and into the space between the members 20 and 21 of the magazine 18. Extending outwardly from the periphery of the disk 83 is a finger 84 the outer end of which has formed therein a notch 85. On either side of the finger 84 are provided guide members 86 which engage the outer surface of the lower ends of the members 20 and 21. The disk 84 is so positioned on the shaft 77 that the finger 84 removes the assembled article and wrapper from the magazine immediately after the transfer fingers have released the article. A revolving brush 87 carried in a bracket 88 secured to the side of the frame 10 serves to dislodge the wrapped article from the notch 85 and direct it into any suitable container.

The shaft 77 has keyed thereto a sheave 89 which is engaged by the driving belt 45 to rotate the hopper 42 as above described. Any suitable means (not shown) may be provided for rotating the shaft 77.

The operation of the apparatus described hereinabove may be briefly summarized as follows:—

The receptacle 12 and magazine 18 are filled respectively with rolled, thin, rubber articles, and tubular wrappers. The cam shaft 77 is continuously rotating, and at the beginning of a cycle 60 of operation, the slide 50 and the transfer fingers 55 and 56 carried thereby are at the extreme right, as viewed in Figure 2. Rotation of the cam 78 moves the slide to the left causing the transfer fingers 55 and 56 to traverse the magazine 18 through the openings 28 and 29 and a tubular wrapper aligned therewith, and enter the receptacle 12 through the opening 17. The ends of the fingers 55 and 56 are open as they enter the receptacle 12 and positioned, respectively, above and below the article disposed on the base 15. As the slide has been moving on its outward stroke the cam roller 73 carried thereby has raised the member 64, which through arm 67, link 69 and pin connection 10, raises the plunger 35 in 75

passage 24, so that a tubular wrapper may be introduced into the passage 24 from the feed tube 19. When the plunger 35 has reached its uppermost position cam 81 comes into play to pivot 5 plate 74 and bring the upper surface thereof under the arm 68 thereby holding the plunger in its raised position against the action of spring 36.

At this point, which is the end of the outward stroke of the slide 50, the cam 82 acts through 10 the follower 63, slide block 60, and roller 58 to move the finger 56 towards the finger 55. This movement of the roller 58 causes the ends of the transfer fingers 55 and 56 to grip the edge of the article. The cam 78 then starts the return stroke 15 of the slide 50, during which movement the cam 82 maintains the fingers in gripping relation with the article. The fingers draw the article from the receptacle 12 and into the tubular wrapper disposed in the magazine. Just before the slide 20 has reached the end of its return stroke the cam 82 permits the roller 58 to drop, thereby permitting the fingers to open and release the article. The release of the article by the fingers is so timed that the article is substantially centered 25 within the tubular wrapper. Immediately following the release of the article the disk 83 has moved around to bring the notch 85 of the finger 84 carried thereby into position to remove the wrapped article from the magazine. Upon the 30 removal of the article from the magazine the cam 81 moves the end of the plate 74 out of engagement with the under surface of arm 68 thereby releasing plunger 35 which is urged downwardly by spring 36 to project a wrapper past the 35 ends of the spring members 32 and 33. The device is then in position to repeat the foregoing cycle of operation.

Having thus described the invention what I desire to obtain by Letters Patent is defined in the appended claims.

40 I claim:

1. An article packaging device comprising a receptacle for receiving disk-shaped collapsible articles to be packaged, a magazine for positioning an open-ended tubular wrapper for said articles, and reciprocating means mounted to move through 45 said wrapper and move one of said articles from said receptacle into and deposit it in said wrapper.

2. An article packaging device comprising a receptacle for receiving disk-shaped collapsible articles to be packaged, a magazine for positioning an open-ended tubular wrapper for said articles, reciprocating means mounted to move through 50 said wrapper and move one of said articles from said receptacle into and deposit it in said wrapper, and means for discharging the wrapped article from the magazine.

3. An article packaging device comprising a 55 receptacle for receiving disk-shaped collapsible articles to be packaged, a magazine for positioning an open-ended tubular wrapper for said article, reciprocating means including cooperating fingers mounted to move through said wrapper and move one of said articles into and deposit 60 it in said wrapper, and means for closing said fingers at one end of stroke to grip an article and opening them at other end of stroke to release the article.

70 4. Article packaging device comprising a receptacle for receiving disk-shaped collapsible articles to be packaged, a magazine for positioning an open-ended tubular wrapper for said articles

and reciprocating means mounted to move through said wrapper and move one of said articles into and deposit it in said wrapper, said magazine including means moving in timed relation to the reciprocating means for aligning 5 said wrapper with said reciprocating means prior to its reciprocation through the wrapper.

5. Article packaging device comprising a receptacle for receiving disk-shaped collapsible articles to be packaged, a magazine for positioning 10 an open-ended tubular wrapper for said articles and reciprocating means mounted to move through said wrapper and move one of said articles into and deposit it in said wrapper, said magazine including a feed mechanism to sequentially advance one wrapper in said magazine during each cycle of movement of said reciprocating means.

6. The method of packaging articles which includes the steps of positioning one end of an 20 open-ended, tubular wrapper adjacent to the edge of a collapsible, disk-shaped article of greater diameter than the diameter of said wrapper, engaging the edge of said article over an area shorter in length than the diameter of said wrapper 25 and exerting a pull on said engaged portion of the article thereby moving said article into and through said wrapper until the article projects beyond each end of said wrapper, and, while the article is being so pulled into said wrapper, 30 distorting said disk-shaped article into an elongated article by bringing the portions thereof on opposite sides of the point of said engagement against the adjacent end of said wrapper and thereby moving said portions toward each other. 35

7. The method of packaging articles which includes the steps of aligning the longitudinal axis of an open-ended tubular wrapper with a diameter of a collapsible, disk-shaped article of greater diameter than the diameter of said wrapper, 40 reaching through said wrapper and grasping the edge of said article over an area shorter in length than the diameter of said wrapper, pulling said article into and through said wrapper by pulling on said grasped portion until the grasped portion 45 has reached a point slightly beyond the end of said wrapper, and, while the article is being so pulled into the wrapper, distorting said disk-shaped article into an article elongated in the direction of said pull by engaging portions of the article on opposite sides of the grasped portion with the adjacent end of said wrapper and thereby pressing said portions toward each other. 50

8. The method of packaging articles which includes the steps of aligning the longitudinal axis 55 of an open-ended tubular wrapper with a diameter of a collapsible, disk-shaped article of greater diameter than the diameter of said wrapper, reaching through said wrapper and grasping an edge of said article over an area shorter in length 60 than the diameter of said wrapper, pulling said article into said wrapper by exerting a pull on said grasped edge and interrupting the pulling operation when the grasped edge has passed through, and to a point slightly beyond, the exit 65 end of the wrapper, and, during said pulling operation, collapsing the article in a direction at right angles to its line of travel by engaging portions of the article on opposite sides of the grasped edge with said wrapper and thereby moving them 70 toward each other.

PETER JOST.

CERTIFICATE OF CORRECTION.

October 25, 1938.

Patent No. 2,134,046.

PETER JOST.

It is hereby certified that the above numbered patent was erroneously issued to Peter Jost, of Akron, Ohio, assignor by mesne assignments, of thirty-seven and one-half per cent to James Tyrrell as trustee and twenty-five per cent to Perry H. Stevens, whereas said patent should have been issued by direct and mesne assignments of thirty-seven and one-half per cent to Frank B. Killian and of thirty-seven and one-half per cent to James Tyrrell as trustees, and twenty-five per cent to Perry H. Stevens, of Akron, Ohio, as shown by the record of assignments in this office; and that the said Letters Patent should be read with this correction therein that the same may conform to the record of the case in the Patent Office.

Signed and sealed this 29th day of November, A. D. 1938.

Henry Van Arsdale

Acting Commissioner of Patents.
